UNITED STATES PATENT OFFICE.

ADOLPH G. KUPETZ, OF NEW ROCHELLE, NEW YORK, ASSIGNOR TO UNDERWOOD ELLIOTT FISHER COMPANY, OF NEW YORK, N. Y., A CORPORATION OF DELAWARE.

TYPEWRITING MACHINE.

Application filed July 15, 1924. Serial No. 726,075.

This invention relates to improvements in space-skipping mechanism for use on typewriting machines, and more particularly has for its object the provision of simple, 5 efficient and inexpensive mechanism designed and constructed to impart to the paper-carriage of the machine intermittently a predetermined number of skipping intervals during its traverse across the machine. 10 There is a certain type of typewriting machines, especially the Underwood make, the design and construction of which is such that its parts may be assembled in a manner suitable to make the machine serviceable 15 in connection with certain typewriter work met with in the office routine of telephone companies. With such companies it is customary to type telephone bills in such a way that the company charge has to be 20 typed successively in a separably designated column of the bill, and alongside this particularly mentioned column is another column upon which is to be typed the United States tax, and there may be still another 25 column opposite the last column, for receiving the inscriptions of a code symbol, and so on. Hence any inscriptions which are to be entered in these successive columns are found to be spaced rectilinearly in the same 30 columns, which means that it becomes desirable in the interest of saving time and enhancing the efficient action of the typewriting machine to make the paper-carriage of the typewriting machine skip or slip over the intervals between the points where these 35 respective inscriptions are to be typed. The present invention accomplishes this result automatically and efficiently at the predetermined points where these inscriptions occur and between which the mentioned spaces 40 intervene.

In carrying out the above object the present invention aims to promote accuracy and speed in typing the mentioned inscriptions in the mentioned columns on a telephone bill, while the bill is properly held in the paper-carriage during the continuous movement of the latter across the machine. Mechanism is provided which will cause the carriage to automatically jump forward two extra letter-spaces to the tax column of the telephone bill and then to jump again two extra letter-spaces to the code column of the same bill without any special attention

on the part of the operator of the machine. 55 A further object of this invention is to so shape the mechanism for carrying out the above results and to so position and arrange the same upon a conventional typewriting machine that it will not be necessary to alter 60 the neighboring parts of the machine where the paper-carriage travels, so as not to unnecessarily complicate the working parts of the machine or cause any change in the usual method of operation or functioning of 65 the neighboring parts. This invention is provided in the form of a simple attachment to the carriage, and performs its office during the movement of the carriage rectilinearly, while all the neighboring parts, 70 co-operating with the carriage to impart a step-by-step movement thereto, continue to perform their duties in a conventional manner.

In all the prior forms of telephone-tax 75 machines where a mutilation of the teeth of the carriage-feed-rack is employed, the automatic skipping movement of the carriage over a toothless section of the rack is arrested by the first tooth at the advancing 80 end of said section striking a single tooth of the stationary carriage-escapement pinion, and requires a second letter-space movement before the teeth of the rack have resumed their full-toothed engagement with 85 the teeth of the pinion. In thus transferring the force of the impact, due to the free movement of the power-driven carriage to a single-tooth engagement between the rack and the pinion, the impact may, after excessive 90 wear, result in mutilation of the teeth.

A feature of the present invention provides that a mutilated or toothless section of the carriage-feed-rack may be partially filled by a toothed insert in the form of a 95 shuttlelike member, which is arranged to reciprocate within the rack-gap, for a predetermined distance, equal to the extent of the carriage-skip; and the teeth thereon are in longitudinal alignment with the rack- 100 teeth, so that when the last rack-tooth that is in advance of the toothless section passes from the restraint of the pinion, the pinion shall have assumed a full-toothed engagement with the toothed insert. While 105 thus the insert is held stationary, through this full-toothed engagement therewith, the typewriter-carriage escapes and moves to

the limit of the gap, the advancing wall of said gap striking the adjoining end face of the pinion-restrained insert. The carriage movement is thus arrested preferably with 5 at least two-rack teeth in engagement with the escapement-pinion. Thus, at all stages of its movement, either through single letter-space distances or through longer column-skipping areas, the escapement-pinion has a 10 positive full-toothed engagement with the associated rack-teeth elements; and the column-skipping movement takes place without disturbing the normal toothed planes of either rack or pinion.

15 Other features and advantages will hereinafter appear.

In the accompanying drawings,

Figure 1 is a sectional side elevation of the 20 part of the machine to which this invention is attached.

Figure 2 is a fragmentary front elevation of the parts of the machine to which this invention is attached.

Figure 3 is a fragmental front elevation 25 of the rack carrying the present invention.

Figure 4 is a view similar to Figure 3, showing the present invention in qualified position.

Figure 5 is a perspective view of a fragmental portion of the rack showing adjacent parts projected relatively thereto.

Figure 6 is a view similar to Figure 4, showing a modification.

Figure 7 is a top plan view of Figure 6.

Figure 8 is a front fragmental elevation of another modified form of this invention.

Figure 9 is a view similar to Figure 8, showing the qualified position of the present invention.

40 Figure 10 is a top plan view of Figure 8.

The present invention is designed to be mounted operatively upon a paper-carriage, and it will be convenient to first describe the neighboring parts which are associated 45 in movement with the paper-carriage. 10 designates the type carried by type-bars 11 positioned to move forward so as to impinge upon the usual revoluble platen 12 mounted upon a platen-axle 13 having its bearings 50 in a platen-frame 14. 15 designates the traveling carriage which travels along a front rail (not shown) and also is slidably guided on a rear rail 16 mounted in position upon the main frame 17. This carriage 55 15 is urged in letter-feed direction by the usual spring drum 18 which is connected to the carriage operatively by means of the usual strap or band 19.

60 The usual escapement or ratchet mechanism, usually found on the typewriting machines, is illustrated, and includes a rack 20 which moves in unison with and is operatively connected to the carriage 15, so that both the carriage and rack will travel 65 in a rectilineal direction across the machine.

The rack is carried by a swinging frame 21 and it is held permanently, during the entire traverse of the carriage, in operative alignment with the pinion 22, fixed upon a shaft 22^a, upon which is also secured fast 70 the escapement-wheel 24, the usual pawl 23 engaging the pinion 22, so that the pinion acts through the pawl 23 to drive the escapement-wheel 24 rotatively. The action of the escapement-wheel 24 is controlled 75 tooth by tooth by means of the relatively fast and loose dogs designated 25 and 26, respectively, and functioning in a manner well known in the art to release the teeth of the ratchet-wheel successively, and to hold each tooth against retrograde movement.

27 designates a universal bar. 28 designates a retractable spring which is secured to the loose dog 26 and holds the same in 85 releasable engagement with the teeth of the escapement-wheel 24 in a manner well known to those skilled in the art.

The present invention may be manufactured in various ways, but the underlying 90 principle of construction and manner of operation is identical. One of the preferred forms of this invention consists in milling out, or otherwise cutting away, the rack 20, which has its teeth 33 interrupted by means 95 of this operation, so as to form a housing 29 having a shoulder 30, and also to form as a continuation of this housing a recess 31 having a shoulder 30^a. The side wall of the housing and recess is formed with an 100 elongated slot 32. An insert or shank 34 is provided which snugly fits the housing 29, so as to abut the shoulder 30 at its inner end. At its outer end the shank 34 is preferably formed integrally with a dog 35 having 105 a number of teeth which are positioned in the same plane, and preferably in alignment with the teeth 33 of the rack 20. Pins 36 are secured to the shank 34 and project operably through the slot 32, so as to be 110 guided therein. A retractable spring 37 is secured at one end to a stud 38 which is fixed upon the rack 20, while the opposite end of the spring 37 is secured operably to the follower or shank 34, the spring serving 115 to hold the shank normally in the position shown in Figures 2 and 3, wherein it will be seen that the outer edge of the shank is spaced away from the adjacent shoulder 30^a formed in the plane of the recess 31, so that the teeth 33 formed in a plane with this shoulder 30^a are also spaced away 120 from the teeth formed upon the dog 35.

It will be understood that this arrangement and mounting of the shank 34 upon 125 the rack 20 may be repeated at various points along the length of the rack where it may be desirable to cause predetermined skips on the part of the paper-carriage to occur with respect to the point of printing 130

engagement of each type-bar 11 with the platen. In this event the teeth formed upon the shank 34 will represent the spaces between the digits or inscriptions which are typed upon a telephone bill in the various columns arranged to receive the same.

A modification of the construction shown in Figure 4 is illustrated in Figures 6 and 7 wherein the rack 20, having the usual rack-teeth 33, is recessed out at 29^a, the recess being of uniform width and depth throughout its length, and arranged in this recess is a dog 34, which, in this instance, is formed with an elongated slot 40, the pins 36 being secured upon the rack, so as to project through this slot 40 and serve to guide the rack 20 relatively to the dog 34. The dog 34 is formed throughout its entire length and under edge with a plurality of teeth 35^a meshing with the pinion 22, while the retractile spring 37 is secured at one end to the stud 38 fixed upon the rack 20, the end of this spring being secured to the lug 39 carried by the dog 34, this spring also holding the dog normally against the inner wall of the recess 29^a, so that the outer edge of this dog will be spaced away from the adjacent shoulder 30^a of the rack 20.

Still another form or modification of the present invention is illustrated in Figures 8 and 9. In this instance the rack 20 is cut away to provide a recess having oppositely-inclined edges 48 and 49, respectively, being flanked at one side by the outwardly-extending web 41, the recess itself opening out at the other side of the rack 20, so that there may be placed and positioned therein the dog or click 43 which is in the form of a lever fulcrumed upon the pin 42 which is secured upon the web 41. The dog 43 is held normally against and in contact with the inclined edge 49 of the recess preferably by means of a leaf or sear spring 44 engaging one edge of the dog 43 with its terminal 45 embodied in this dog. The spring 44 is also preferably coiled around the fulcrum end of the dog 43, and extends downwardly so that its stem 46 may be operably and fixedly secured at 47 in the rack 20. This dog 43 is formed with teeth 50 adapted to be in longitudinal alignment with the teeth 33 of the rack 20. Normally the spring 44 holds the dog 43 diagonally of the longitudinal axis of the rack 20, so that the outer longitudinal edge of this dog 43, also inclining diagonally, is spaced away from the inclined edge 48 of the recess.

In operation, with the invention secured in the position indicated and suitably housed upon the rack 20, it will be possible, by such means, to cause the paper-carriage or letter-feeding carriage of the typewriting machine to skip automatically between predetermined neighboring points along the carriage travel depending upon the positions on the tele-

phone charge sheet where the digits are to be typed in spaced apart relation rectilineally in the several columns thereof. In typing telephone bills, as already intimated, the company charge, the United States tax and 70 the code symbol are to be printed in different columns on the sheet, and the points where they are to be printed must be brought up to the printing point where the type-bars make impressions upon the sheet. Ordinarily by skipping two teeth and moving the carriage a distance equal to these teeth, the carriage can be made to traverse from the proper point in one column where the last digit has been typed to the point in the next 80 adjacent column where the first digit of a new number is to be typed in this particular column, and so on in moving the carriage to the next predetermined position for typing a digit in the next adjacent column. 85

What takes place during the performance of the last-named function so far as the parts of this present invention are concerned, is as follows:—As the operator is depressing the keys of the machine incidental to a typing action, the spring-drum 18 is set in action for moving and urging the carriage 15 rectilineally, so that the rack 20 also moves rectilineally with the carriage, with the teeth 33 held in meshing engagement 95 with the teeth of the pinion 22, so that the rack and pinion are held in driving-and-driven engagement, the pinion being driven in step-by-step fashion, owing to the pawl-and-ratchet mechanism forming part of the 100 usual escapement device on the machine.

The retractile spring 28 is stout enough to exert just so much tension upon the loose dog 26 as will be effective to allow the ratchet or escapement wheel 24 to slip thereover, 105 step by step, or tooth by tooth, so that the step-by-step movement of the rack and carriage takes place against the tension of the spring 28, and the pinion 22 is active continuously as long as the teeth proper 33 of 110 the rack 20 are engaged by it, but immediately as the teeth of the dog 33 come into engagement so as to contact with any of the teeth of the pinion 22 forming part of the escapement mechanism, the tension of the 115 spring 28 is no longer overcome by the rack 20 during the letter-feed movement of the carriage 15, with the result that the carriage is about to slip at this predetermined point.

It will be seen that the last digit has been 120 typed in the company charge column in the telephone bill or sheet after the latter has been placed properly behind the paper-shelf and against the platen, and that the carriage now has to skip over the distance equal to 125 as many teeth on the rack as will measure the distance apart between this digit and the point where the next digit is to be typed in the United States tax column of the same telephone bill; the parts are now in the posi- 130

tion shown in Figure 3 with the rack moving in the direction shown and indicated by the arrow from left to right in this given instance, the carriage moving in the same direction. It will be seen that the tooth X among the rack teeth 33 is in mesh with a tooth on the pinion 22; at this time, when a type 10 is swung upwardly for printing the last digit in the company charge column, 5 the loose dog 26 is rocked out of engagement with the escapement-wheel tooth 41^a and is drawn to the left by the spring 28, and then the fixed dog 25 is rocked out of engagement with the adjacent tooth 41^a to prevent the rotation of the escapement-wheel 24 and to cause a temporary lull of the paper-carriage 15 until the next key is struck. On the return stroke of the type 10, the dog 25 is rocked out of engagement with the tooth 41^a and the dog 26 is rocked into the path of the wheel tooth 42^a, while the other dog 25 meets the tooth 42^a of the wheel. The escapement-wheel 24 is now free to advance the distance of one tooth, and as the 10 rack 20 meshes with the pinion 22 and is urged in letter-feed direction by the spring-drum 18, the carriage 15 is caused to advance, which causes the rotation of the escapement-wheel 24, which movement causes 15 the dog 26 to move to initial position against the tension of spring 28. It is understood that the escapement-wheel 24 is limited in extent of movement by engagement of the fast and loose dogs 25 and 26, respectively.

20 During the action just explained and while the rack 20 is still moving incidentally to depressing the keys of the machine, the tooth Y formed on the shank 34 is moving forwardly as the tooth X is moving beyond and out of mesh with the pinion 22. Now, upon the engagement of this tooth Y with the pinion (see Figure 3), the rack is unable to 25 overcome the tension of the spring 28, this time, in order to turn the pinion 22 and escapement-wheel 24, and so to continue the step-by-step movement of the rack with respect to the pinion; because as the rack continues to move, urged on by the spring-drum 18, with the carriage moving concurrently, the rack slides rectilineally of the shank 34, which latter is held stationary by the pinion 22; this sliding, slipping or skipping movement of the rack replacing and 30 eliminating the step-by-step movement of the carriage, and this relative sliding movement of the rack 20 also continuing until the edge 30^a of the slot 32 engages the outer edge of the shank 34. As the rack slides, the slotted portion 32 thereof is guided upon the pins 36, against the tension of the relatively lighter spring 37, so that immediately when the edge 30^a of the rack engages the outer edge of the shank 34 it pushes this shank along with it, the latter acting as a follower 35 and causing the rack 20 to exert the neces-

sary force to again overcome the tension of the spring 28 and to allow the escapement mechanism to operate again, by causing the teeth 35 formed upon the shank 34 to mesh with the teeth of the pinion 22 in exactly 70 the same manner that the teeth 33 of the rack 20 have meshed with this same pinion to produce the step-by-step movement of the carriage 15. Just as soon as the mentioned teeth 35 of the shank 34 moves out of mesh 75 with and beyond the teeth of the pinion 22, and while the pinion is still in mesh with the teeth proper of the rack, the spring 37 relaxes and restores the shank 34 to normal position, so that its inner end again engages the shoulder 30 formed upon the housing 29. During the relative sliding action of the rack with respect to the stationary shank 34 produced by the engagement of the dog teeth 35 with the pinion 22, the step-by-step 80 movement of the carriage has ceased and the carriage has slipped over to the exact point where the type 10 may produce the impression of a digit in the United States tax 85 column of a telephone bill sheet. The slipping operation is now repeated again automatically by the same mechanism at the next point where the digit is to be typed in the code symbol column of this bill.

90 The modification shown in Figures 6 and 7 is concerned only with providing a greater number of teeth 35^a upon the same rack 20 and in reversing the location of the slot and pins for imparting a rectilineal sliding motion to the rack with respect to the follower or dog 34. The action of the rack 20 when the dog 34 engages the pinion through its teeth 35^a is exactly the same as that which has been described concerning dog shank 34 illustrated in Figures 3 and 4, except that a longer interval of time will elapse before the pinion 22 can clear the teeth of the dog 34 shown in Figure 6. The slot 40 is formed upon the dog 34, the pins which are guided in this slot and held operably therein being secured directly upon the rack 20, the spring 37 being secured upon the stud 38, which, in this instance, is mounted upon the upper edge of the rack 20 (where in Figures 3 and 4 the sides are mounted on the side of the rack), the outer end of this spring being secured upon a lug 39 formed upon the dog 34.

100 The other modification shown in Figures 8 and 9 is concerned with providing a pivotal movement rather than a sliding movement on the part of the dog that engages the pinion and that is responsible for rendering the step-by-step action of the escapement mechanism ineffective at predetermined 105 points already considered. The action of the pawl or dog in this instance is also the same as has been explained hereinbefore, because it plays in the recess similar to the action of the shank 34 in its recess, against the tension 110

of the sear or leaf spring 44. As soon as the dog 43 engages the inclined edge 48 the rack begins to push this pawl in meshing engagement with the pinion 22, so as to rotate the same in step-by-step fashion until this pawl or dog 43 is disengaged from the pinion whereupon the leaf spring 44 is retracted to normal position, carrying with it the dog 43.

From the foregoing description, it is thought that the advantages of the present invention will be understood and appreciated by those skilled in the art, and that its susceptibility for long service and its tendency to resist derangement will also be appreciated.

It will be noted that the carriage-feed rack is provided with a toothed insert confined to a vibratory movement between walls formed in the rack; that the relative length of the toothed insert to the space between these two walls predetermines the extent of a free carriage-movement; that the carriage-movement so effected may be a single letter-space distance or a continuous distance of greater extent; that the pinion whether in engagement with the rack, the toothed insert or both, always has a full-toothed engagement therewith; and that the carriage-skipping movement is automatically effected without relative separation of the working planes of the rack or the escapement-pinion.

Variations may be resorted to within the scope of the invention, and portions of the improvements may be used without others.

Having thus described my invention, I claim:

1. In a typewriting machine, the combination of a power-driven carriage, a carriage-feeding mechanism including a carriage-rack engaging a pinion controlled by escapement-devices for step-by-step letter-space-feeding distances, and means movable within the rack to automatically effect a letter-space movement of the carriage independently of the escapement-devices.

2. In a typewriting machine, the combination of a power-driven carriage, escapement-mechanism including a rack and a pinion whereby a step-by-step movement is imparted to said carriage, and means movable on the rack and engageable with said pinion for a full-toothed engagement therewith, whereby the carriage skips automatically during the normal course of writing.

3. In a typewriting machine, the combination of a power-driven carriage, carriage-feeding mechanism therefor, including a pinion and a mutilated toothed rack, and means to partially restore the teeth of the rack at the point of mutilation thereof by a movable toothed-insert.

4. In a typewriting machine, the combination of a power-driven slideable carriage, carriage-feeding means for sliding said carriage step by step letter-space distances including

a pinion and a carriage-rack having a driving and a driven relationship, and a member moving with said carriage-rack and having a positive toothed engagement with the pinion to automatically cause the carriage to have a sliding relation with respect to said carriage-feeding means.

5. In a typewriting machine, the combination of a power-driven carriage, an escapement-pinion, a carriage-feed rack to engage with the pinion, having an open toothless space, and a rack-section operative to partially restore the teeth within the toothless section of the carriage-rack, and co-operate with the pinion at a predetermined point in the travel of the carriage to automatically effect a column-skipping movement of the carriage, and then become operative as a carriage-feed rack for letter-spacing the carriage.

6. In a typewriting machine, the combination of a power-driven carriage, an escapement-controlled pinion, and a carriage-feed rack operative at all positions of the carriage-feeding movement to have a toothed engagement with the pinion, said feed-rack having a toothless section provided with a slidable toothed insert operative therein to automatically effect a column-skipping movement of the carriage when the pinion releases the carriage-rack and engages the toothed insert.

7. In a typewriting machine, the combination of a power-driven carriage, a rack moving with said carriage, escapement carriage-feeding mechanism including a rack and a pinion to impart to said carriage a normal step-by-step movement, and means carried by said rack and yieldable relative to the rack upon engagement with said pinion to allow the rack to slip past said pinion as said carriage moves concurrently therewith.

8. In a typewriting machine, the combination of a power-driven carriage, an escapement mechanism including a ratchet-wheel having a pinion meshing with a rack to control the movement of said carriage in step-by-step direction, and means carried by said rack and meshing with said pinion and actuated thereby to yield rectilinearly in said rack, thereby converting the movement of said carriage into a slideable movement relatively to said pinion.

9. In a typewriting machine, the combination of a power-driven carriage, means for feeding the carriage step by step single letter-space distances including a rack and a pinion, and means carried by the rack and automatically operable when the carriage reaches a predetermined position, to effect a carriage-feed movement greater than a letter-space distance and allowing to be normal the plane of the rack to the pinion.

10. In a typewriting machine, the combination of a power-driven carriage-rack, a

pinion permanently mounted with relation to and meshing with said rack, means holding said rack in positive mesh with said pinion, said rack being cut away to provide for 5 a toothless recess therein, and means movably mounted within said recess and having teeth meshing with said pinion, whereby said rack is automatically released from the control of said pinion and may slip a distance predetermined by the length of the recess.

11. In a typewriting machine, the combination of a carriage-feeding mechanism including a rack held in mesh with a pinion, 15 and a member movably mounted within said rack and having teeth arranged in the same plane with the teeth of said rack and meshing with said pinion, said member upon engagement of its teeth with said pinion, during 20 the movement of said rack, allowing said rack to move parallelly with itself, thereby releasing said rack from the control of said pinion.

12. In a typewriting machine, the combination of a rack, a stationary pinion meshing rotatably with said rack and driven thereby, ratchet mechanism allowing said pinion to move in step-by-step fashion only, a member carried along with said rack, an 30 abutment carried by said member and stopped by said pinion, and means allowing said rack to move relatively to said member upon the latter being stopped by said pinion with its teeth still in mesh with said pinion, said pinion engaging said member, 35 whereby to be driven thereby in the continuous movement of said rack after the latter

has stopped moving relatively to said member.

13. In a typewriting machine, the combination of a pinion, a rack held in meshing relation with said pinion, said rack being cut away to provide a recess, a dog of lesser length than said recess mounted snugly within the recess, means for slidably holding said dog in said recess, teeth formed upon said dog to align with the teeth of said rack, and means for normally and yieldingly holding said dog in said recess. 40

14. In a typewriting machine, the combination of a ratchet-controlled pinion, a rack movable rectilinearly and having teeth normally meshing with said pinion during the traverse of the rack, said rack being cut away to provide a housing and a slot in continuation of said housing, a dog snugly fitting said housing and having an integral shank projecting into the inner end of said slot and provided with teeth arranged in longitudinal alignment with the teeth of 50 said rack, said rack being free of teeth along that length of the slot traversable by said dog, pins engaging said shank to hold it within said housing, a longitudinally slotted portion in which said pins are slidably and operably held to permit the slotted portion 55 of said rack to move relatively with respect to said shank, a pin on said rack-proper, and a retractable spring having one end secured upon said pin and the other end secured to 60 said shank and yielding against the movement of said rack relatively to said shank. 70

ADOLPH G. KUPETZ.
